CLAIM

(21) Appl. No.: **29/112,805**

The ornamental design for a computer generated image for a display panel or screen, as shown and described.

(22) Filed: **Oct. 25, 1999**

DESCRIPTION

(51) LOC (7) Cl. **14-02**

FIG. 1 is a front view of a computer generated image for a display panel or screen;

(52) U.S. Cl. **D14/486**

FIG. 2 is a front view of a second embodiment thereof;

(58) Field of Search D14/485-95; D18/24-33;

FIG. 3 is a front view of a third embodiment thereof;

D19/6; D20/11; D21/324-33; 345/326,

FIG. 4 is a front view of a fourth embodiment thereof;

339-58

FIG. 5 is a front view of an fifth embodiment thereof;

D19/6; D20/11; D21/324-33; 345/326,

FIG. 6 is a front view of a sixth embodiment thereof;

339-58

FIG. 7 is a front view of a seventh embodiment thereof; and,

D19/6; D20/11; D21/324-33; 345/326,

FIG. 8 is a front view of an eighth embodiment thereof.

339-58

The broken line drawing of a display panel or screen in all views is for illustrative purposes only and forms no part of the claimed design.
